FISHING LURE OR SIMILAR ARTICLE

Charles Spence, Memphis, Tenn., assignor to Strike King Lure Co., Inc., Memphis, Tenn.

Filed Apr. 9, 1973, Ser. No. 349,554

Term of patent 14 years

Int. Cl. D22—05

U.S. Cl. D22—27

FIG. 1 is a top plan view of a fishing lure or similar article embodying my design;

FIG. 2 is a bottom plan view;

FIG. 3 is a side elevational view; and

FIGS. 4 and 5 are end elevational views of opposite ends.

I claim:

The ornamental design for a fishing lure or similar article, as shown.
